(57) **CLAIM**

The ornamental design for a handle for surgical instrument, as shown and described.

DESCRIPTION

1. **HANDLE FOR SURGICAL INSTRUMENT**

FIG. 1.1 is a perspective view of a HANDLE FOR SURGICAL INSTRUMENT;

FIG. 1.2 is a front elevational view thereof;

FIG. 1.3 is a rear elevational view thereof;

FIG. 1.4 is a left side elevational view thereof;

FIG. 1.5 is a right side elevational view thereof;

FIG. 1.6 is a top plan view thereof; and

FIG. 1.7 is a bottom plan view thereof.

The broken lines shown in FIGS. 1.1-1.7 illustrate portions of the HANDLE FOR SURGICAL INSTRUMENT that form no part of the claimed design.

1 Claim, 7 Drawing Sheets
